(57) **CLAIM**

The ornamental design for a piercing stylet with non-contacting distal tip, as shown and described.

DESCRIPTION

FIG. 1 is a right side view of the piercing stylet with non-contacting distal tip;

FIG. 2 is a left side view of the piercing stylet with non-contacting distal tip;

FIG. 3 is a front view of the piercing stylet with non-contacting distal tip;

FIG. 4 is a right side 45 degrees from the front view of the piercing stylet with non-contacting distal tip;

FIG. 5 is a left side 45 degrees from the front view of the piercing stylet with non-contacting distal tip;

FIG. 6 is a right side 45 degrees from the rear view of the piercing stylet with non-contacting distal tip;

FIG. 7 is a left side 45 degrees from the rear view of the piercing stylet with non-contacting distal tip; and,

FIG. 8 is a rear view of the piercing stylet with non-contacting distal tip.

The piercing stylet with non-contacting distal tip is shown with a symbolic break in its length. Any portions not shown after the break line form no part of the claimed design.

1 Claim, 6 Drawing Sheets
